UNITED STATES PATENT OFFICE.

EDWARD J. SEGRELL, OF NEWARK, NEW JERSEY.

SKIRT.

1,147,897.

Specification of Letters Patent. Patented July 27, 1915.

Application filed October 1, 1914. Serial No. 864,435.

To all whom it may concern:

Be it known that I, EDWARD J. SEGRELL, a citizen of the United States, residing at Newark, in the county of Essex and State 5 of New Jersey, have invented certain new and useful Improvements in Skirts, of which the following is a specification.

This invention consists in certain improvements in skirts of the type illustrated 10 by my Letters Patent Nos. 891,868 and 903,326, wherein for the purpose of adjusting a skirt to waists of different sizes the waist-band of the skirt has each side of the back center thereof means for altering its 15 girth, this result being in that case attained by forming a vertical lapel extending downwardly from the waist-band a suitable distance and detached at its sides from the body of the skirt and placing on the lapel 20 two hooks or the like, one at each side of and in the waist-band part of the lapel, and on the waist-band itself each side of the lapel a series of eyes or the like any one of which may be engaged by the correspond- 25 ing hook.

To simplify the construction of skirts of this class, increase their durability, make them fit to better advantage in respect both to appearance and comfort are the principal 30 objects of the present invention, which will be found fully illustrated in the accompanying drawings, wherein,

Figure 1 is a rear elevation of the improved skirt; Fig. 2 an inside elevation of 35 the upper back part of the skirt; Fig. 3 is a top plan view, on a larger scale, of the back of the skirt; and Fig. 4 is a horizontal sectional view on line $x-x$ of Fig. 2.

The skirt shown in the accompanying 40 drawings comprises a body a made up, except as hereinafter indicated, in any desired way, and a waist-band b , which preferably, though not necessarily, consists of a strip of suitable stout material folded lengthwise, 45 being then fitted over the upper edge of the body and stitched in place. For applying and removing the skirt it is provided with a placket c , preferably at the left of the front center and with a hook and eye or 50 other fastening device d whose members are attached at opposite sides of the placket to the waist-band.

Adverting now, to the novel features of 55 the improved skirt and describing them in the preferred form shown in the said drawings, at the back center of the skirt body

from the upper edge downwardly suitable distances the said body is folded at $e-e$, $f-f$ and $g-g$, to produce box-plait i and the two reverse box-plaits j , the folds 60 $f-f$ preferably being in close proximity to each other. The box-plait i is formed in only the skirt-body a ; that is to say, the said box-plait i is formed in the skirt body before the waist-band strip b is fitted and 65 stitched in place along the top of the skirt body, with the result that the waist-band is perfectly smooth or unfolded in the part thereof represented by the approximate width of the said box-plait i . But the folds 70 $g-g$ of the box-plaits j are formed after the waist-band strip has been applied and stitched in place, in consequence of which said folds affect the waist-band as well as the skirt body. Likewise, before the waist- 75 band strip is applied and stitched in place two parallel lines of stitching k are run from the upper edge of the body downwardly a suitable distance close to each of the folds $f-f$ and through the three thick- 80 nesses of material making up the box-plait i and each box-plait j , the same permanently preserving the folds $f-f$, as will be obvious; whereas after the waist-band strip has been applied and stitched in place a line of 85 stitching l is run from the upper edge of the waist-band downwardly a suitable distance close to and parallel with each fold g and through the two thicknesses thereof, preserving permanently the said folds $g-g$. 90 Across the lower ends of the lines of stitching k and l may be extended one or more, preferably two, lines of stitching m . At suitable intervals to the right and left from the thus box-plaited back center 95 of the skirt the waist-band is provided with a series of eyelets n . On the folds $g-g$, on the side of each which faces away from the other (see Fig. 3), are placed the hooks o , each adapted to engage in one of the eyelets 100 of the corresponding series n . Other securing devices than hooks and eyes may obviously be employed. Thus constructed the skirt is adapted, as will be clear, to be adjusted to different waist-measures—accomplished by shifting either or both of the hooks o to one or the other of the eyes of the corresponding series. This, moreover, without formation of any openings whatever that is incident to the part of the skirt directly 105 concerned in the adjustment thereof, which is an element of considerable importance in

that it saves the manufacturer extra work in finishing the skirt and insures against such opening exposing the undergarment of the wearer.

5 What I term a "shield" is formed by that part of the back of the skirt which extends from the upper edge of the waistband to and including the stitching *m m* and from one to the other fold *g*; it is, in 10 effect, a broad or major box-plait which is composed (as herein illustrated, for example) of the minor box-plaits *i* and *j* and whose folds *g* are preserved well-defined and trim by the stitching *l l*. When the 15 skirt is adjusted to the wearer, this shield serves to cover the shiftable folds *p p*, giving a neat appearance to the adjusting back portion of the skirt. Moreover, while it rests perfectly flat over the flat part of the 20 wearer's back midway between and in the horizontal line of the hips, the skirt can below the shield adjust itself to the wearer's form at the buttocks due to the fullness derived from the continuation *i'* of the box- 25 plait *i*, the folds of which (*i'*) are left unstitched, as shown in Figs. 1 and 2.

Having thus fully described my invention, what I claim as new and desire to secure by Letters Patent is:—

30 1. A skirt having at the back and extending downwardly from the upper edge thereof toward but not below the buttocks part thereof two spaced plaits and between said

plaits a box-plait extending downwardly from the upper edge thereof below said buttocks part, the adjoining folds of said box-plait being secured in fixed relation to each other from said upper edge downwardly to but free below said buttocks part, and means to releasably attach the first two plaits to 40 the adjacent material of the skirt in each instance at a series of laterally extending points.

2. A skirt including a skirt-body and a waist-band stitched to said body and said skirt having at the back center a box-plait extending from the upper edge of said body downwardly below the buttocks part thereof and having its adjoining folds secured in fixed relation to each other above but free 45 below said buttocks part, the waist-band extending straight or unfolded across the box-plait, said skirt also having its body and waist-band formed with other plaits one 50 each side of the box-plait and extending 55 downwardly toward but not beyond said buttocks part, and means to releasably attach the latter two plaits to the adjacent material of the skirt in each instance at a series of laterally extending points.

In testimony whereof I affix my signature in presence of two witnesses.

EDWARD J. SEGRELL.
